S. E. WITT

RECEIVER

Filed Jan. 27, 1921

Fig. 3.

UNITED STATES PATENT OFFICE.

SAMUEL E. WITT, OF CHICAGO, ILLINOIS.

RECEIVER.

Application filed January 27, 1921. Serial No. 440,549.

To all whom it may concern:

Be it known that I, SAMUEL E. WITT, a citizen of the United States, residing at Chicago, in the county of Cook and State of Illinois, have invented a certain new and useful Improvement in Receivers, of which the following is a full, clear, concise, and exact description, reference being had to the accompanying drawings, forming a part of this specification.

My invention relates to receivers and has to do more particularly with receivers of the so-called loud speaking type.

One of the features of my invention is the provision of a diaphragm operatively connected to an armature pivotally associated with the receiver electromagnet and with the diaphragm normally flexed preferably by means of a spring tending to press it toward the pole-piece of the electro-magnet. Thus the diaphragm is under a normal flexure by means of the spring with the armature thus held closest to the pole-piece of the electromagnet. I have found that with my improved device the diaphragm is vibrated so as to produce a more natural voice tone, and this is particularly true on the high notes where used for repeating the music as from phonographs. The reproduction comes true to pitch throughout the normal range, not a lower pitch as heretofore.

This is brought about, I believe, due to the flexed arrangement of the diaphragm and the cooperating parts, of the electromagnet connected therewith. The diaphragm is thus held under continuous tension and vibrates truer to the variations in magnetic pull of the electromagnet, than where the diaphragm is free to partake of a greater amplitude of vibration and thus more free to vibrate out of tune with the magnetic variations.

For a better understanding of my invention reference is to be had to the accompanying drawing in which—

Fig. 1 is a transverse section through my improved receiver along the line 1—1 of Fig. 2;

Fig. 2 is a bottom view of Fig. 1;

Fig. 3 is a top or plan view of Fig. 1;

Fig. 4 is a transverse section along the line 4—4 of Fig. 3;

Fig. 5 is a perspective view of the armature and a part of the connector extending to the diaphragm,

Fig. 6 is the mounting block and spring which act upon the armature and diaphragm to effect a normal flexure thereof, and

Fig. 7 is a detail view of the pole-piece.

Referring now more in detail to the preferred form of my invention as shown herein, it comprises a diaphragm mounting which includes a front plate 8 having a threaded portion 9 to which a horn 10 is threaded. A ring 11 is secured to the front plate 8 by means of screws 12 in order to clamp the diaphragm 13 between the usual yieldable elements 14 which are preferably small rubber tubes. I also insert a vibration reducing block 15 preferably of glass between the diaphragm and front plate 8.

Secured to the ring 11 is a bridge-piece 16 fastened by means of screws as shown by the dotted lines in Fig. 1. This bridge-piece 16 carries insulated binding posts 17—18 which receive the conductors 19—20 leading from the transmitter 21 and battery 22. Of course, it is to be understood that the device is not limited to use in the particular circuit illustrated.

Connected to the diaphragm 13 is an actuating means in the form of an electromagnet having a circular helix 23 supported upon a core 24 which acts as a continuation of the heel-piece 25 and is integral with the threaded stud 24'. The helix is preferably made up of insulated copper wire, lock-stitched with silk thread, and then pressed over the core, the stitching acting as additional insulation between the helix, and the core and heel-piece. The electromagnet 23 is secured to the mounting plate 26 by means of this stud 24' which is inserted through the hole in mounting 26 and into the sleeve 27. Between the sleeve 27 and plate 26 is secured a leaf spring 28 in order to firmly hold the mounting 26 and its parts in adjusted position. This adjustment is effected by the turning of the screw 29 which is threaded into the rod 27.

In order to actuate the diaphragm by means of the electromagnet I preferably employ an intermediate armature 30 which is

adjustably connected with the diaphragm by means of the screw eye 31 which passes through the threaded plates 32, 33 placed upon opposite sides of the mica diaphragm 5 and securely clamping the same. This screw eye is hooked over a pin end of the armature 30 at a point beyond the core 24 so that there is a slight amplification of movement of the diaphragm. That is, the diaphragm has a greater amplitude of vibration than the vibration of the armature at the core. The pivoting end of the armature 30 rests upon the up-right of the member 25 and abuts the bracket 34 which is secured to the plate 26. This bracket 34 has a central portion struck back from the up-right so that a securing means for the armature may be passed through the small hole 35 and around this struck back portion, this 10 securing means being in the form of a fine silken cord.

In order to secure a proper cooperation of the electromagnet and diaphragm I use tension means to normally flex the diaphragm and hold the armature, in the form of a leaf spring 36 which presses against the armature at a point preferably opposite the core. This spring 36 is supported by a non-magnetic-material block 37 having 25 grooves 38 in which the spring 36 is adjustably carried. This adjustment is brought about due to block 37 being slotted at 39 so that the block will yield in order to clamp the spring in its adjusted position 30 when the screw 40 which passes through one side of the block and threads into the other is turned. This block 37 is adjustably supported, preferably by resting upon a knife edge pivot 41 which engages the V-shaped 35 groove 42 in the block. Now in order to adjust the block and thereby vary the tension of the spring 36, the free end of the block carries a screw-eye 43 which passes through the plate 26 and is engaged by the 40 thumb-nut 44. It will thus be seen as the nut 44 is rotated block 37 rotates on its 45 pivot and may thus vary the tension of the spring 36 thereby securing the proper normal deflection of the diaphragm.

50 In adjusting the device the armature is connected to the diaphragm by means of the screw eye 31. Then by means of the adjusting nuts 29 and 44 the tension of spring 36 and adjustment of armature 30 is
55 varied until the desired air-gap between the armature and core is secured and a sufficient deflection of the diaphragm to secure a suitable operation thereof.

It will be noted that the electromagnet, 60 armature and tension spring with its adjusting means are mounted as an adjustable unit, this being of great advantage in that adjustment may be effected at the various points such as at adjusting nut 44, nut 29, 65 or diaphragm without affecting the other

parts. That is, the adjustments may be made independently of each other.

In the use of the device on a low voltage such as from about 6 to 9 volts, I have gotten excellent results with a coil having a 70 resistance of about three ohms with approximately 200 turns of about thirty-two single silk wire. When connected up with the ordinary local battery transmitter of about ten to twenty ohms resistance excellent loud 75 speaking qualities were secured.

The device has also been particularly useful for loud reproduction of phonographic music wherein a suitable transmitter is placed inside the phonograph horn and then connected to the receiver as shown in Fig. 1. On reproducing the voice on my improved direct current receiver, when connected to the phonograph as referred to, it produces a more natural voice tone, especially on the high notes. It comes true to pitch throughout the entire reproduction, not a lower pitch as heretofore. Heretofore where loud speaking receivers of the permanent magnet type have been used for phonographic reproduction, so far as I am aware, the reproduction was of a lower pitch so that a tenor sounded more like a baritone. This I have overcome by the device shown and claimed herein. 95

In prior devices wherein permanent magnets are used in connection with the electromagnet and where the receivers are connected for direct current reproduction with the transmitter and battery connected for a direct current flow, and where no normal external tension is applied so as to deflect the diaphragm, the diaphragm is under its greatest strain and deflection when the transmitter is inert. At this time the resistance 100 of the transmitter is lowest so that the greatest pull is exerted by the electromagnet and thus the diaphragm under greatest deflection. As soon as the transmitter is operated 105 the resistance of the circuit through the receiver coil is increased so that the diaphragm falls away from the electromagnet. Also as the pitch of the actuating tone increases, the transmitter vibrates more and the resistance increases still further thus permitting 110 a further recession of the diaphragm. At this time, of course, it is farthest away 115 from the electromagnet and at a time when the finest work is expected because the high notes are being transmitted. Also it is to 120 be noted that as an armature recedes from the pole-pieces of the electromagnet, the pull decreases directly with the square of the distance. Where no external tension is 125 brought to bear upon the diaphragm, at the time of transmission of the highest notes and with the diaphragm furthest from the electromagnet, the weakest actuating current is operating upon the diaphragm and also at a time when it is free to partake 130

of the greatest amplitude of vibration. I have found that due to this construction in such receivers the reproduction of high notes in talking, singing or from phonographic music the receiver operates at a lower frequency than the variations in the magnet flux. A reproduction is thus secured which is not at all true with the original sound.

10 These defects I have overcome by my improved device, the reproduced tune being substantially true to the original sound and also of great volume, holding true to a greater range than I have been heretofore able to secure.

I claim—

1. In a receiver, a diaphragm, an electromagnet, a normally non-polarized armature for the electromagnet rigidly connected to the diaphragm, and a spring acting against the armature and movable therewith and normally flexing the diaphragm and armature toward the electromagnet.
2. In a receiver, a diaphragm and mounting, and a unit adjustably mounted relative to the diaphragm, said unit comprising an electromagnet and non-polarized armature connected to the diaphragm and a spring acting upon the armature and flexing the diaphragm, and means for adjusting the spring to vary the pressure upon the armature and normal flexure of the diaphragm.
3. In a receiver, a diaphragm and mounting, a bridge fixedly secured to the diaphragm mounting, a unit comprising an electromagnet and armature connected to the diaphragm and a single mounting carrying the electromagnet and armature, and means for adjustably supporting said unit mounting upon the bridge whereby adjustment of the single mounting will simultaneously adjust the magnet and armature relative to the diaphragm.
4. In a receiver, a diaphragm and mounting, a bridge secured to the diaphragm mounting, a unit comprising an electromagnet and armature connected to the diaphragm and an adjustable spring acting upon the armature and flexing the diaphragm, and means for adjustably supporting said unit upon said bridge.
5. In a direct current receiver, a diaphragm, an electromagnet and non-polarized armature connected with the diaphragm and positioned relative thereto so that the diaphragm and armature vibrate substantially parallel and the direction of motion of the diaphragm and armature coincide, resilient mechanical means acting upon the armature and diaphragm so as to press the armature toward the pole piece of the magnet and normally flex the dia-

phragm sufficiently to maintain the amplitude of the operating vibrations of the diaphragm within the concave formed by the 65 flexure.

6. In a receiver, a diaphragm, a supporting bridge, a mounting adjustably carried by the bridge piece, an electromagnet, an armature carried by the mounting, means 70 for operatively connecting the armature to the diaphragm, and a tension spring tending to press the armature toward the electromagnet adjustably carried by the mounting.

7. In a receiver, a diaphragm, an electromagnet and armature operatively connected to the diaphragm, a mounting for the electromagnet and armature, a block pivotally attached at one end to the mounting and carrying a spring at the other end for placing tension upon the armature, and an adjusting screw connected to an intermediate portion of the block so as to move the block to vary the tension of the spring upon the 85 armature.

8. In a receiver, a diaphragm, an electromagnet and armature operatively connected to the diaphragm, a mounting for the electromagnet and armature, a lever pivotally attached to the mounting and carrying a spring, said spring placing a yielding tension upon the armature whereby the spring moves with the operating movements of the armature, and an adjusting screw 90 connected to the lever so as to move the lever to vary the tension action of the spring upon the armature.

9. In a direct current receiver, a diaphragm, an electromagnet, an armature 100 having adjustment relative to the electromagnet to vary its air gap and operatively connected by a rigid link to the diaphragm, a resilient member for placing tension to give a substantial normal flexure to the diaphragm, and means for varying the tension upon the diaphragm at different air gaps of the electromagnet and armature.

10. In a direct current receiver, a diaphragm, an electromagnet, an armature 110 having adjustment relative to the electromagnet to vary its air gap and operatively connected by a rigid link to the diaphragm, a resilient member for placing tension to give a substantial normal flexure to the diaphragm, means for varying tension upon the diaphragm, and means for varying the air gap for different tensions on the diaphragm.

In witness whereof, I hereunto subscribe 120 my name this 19th day of January, A. D., 1921.

SAMUEL E. WITT.
